CLAIM

The ornamental design for an portable wiper dispenser, as shown and described.

DESCRIPTION

FIG. 1 is a perspective view of a first embodiment of a portable wiper dispenser showing the new design;
 FIG. 2 is a top plan view thereof;
 FIG. 3 is a bottom plan view thereof;
 FIG. 4 is a front view thereof;
 FIG. 5 is a rear view thereof;
 FIG. 6 is a right side view thereof;
 FIG. 7 is a left side view thereof;
 FIG. 8 is a perspective view showing a second embodiment of the new design;
 FIG. 9 is a top plan view thereof;
 FIG. 10 is a front view thereof;
 FIG. 11 is a rear view thereof;
 FIG. 12 is a right side view thereof;
 FIG. 13 is a left side view thereof;
 FIG. 14 is a perspective view of the first embodiment without the optional strap;

FIG. 15 is a bottom plan view of the first embodiment without the optional strap; and.

FIG. 16 is a perspective view of the second embodiment without the optional strap.

The bottom view of the second embodiment shown in FIGS. 8-13 is identical to the bottom view of the first embodiment, as shown in FIG. 3.
